UNITED STATES PATENT OFFICE.

JOHN SCHERNER, OF CUDAHY, AND EDWARD HUTCHENS, OF EAU CLAIRE, WISCONSIN, ASSIGNORS TO PIERCE WRAPPING MACHINE COMPANY, OF CHICAGO, ILLINOIS, A CORPORATION OF ILLINOIS.

WRAPPING MACHINE.

Original application filed April 3, 1916, Serial No. 88,563. Divided and this application filed July 10, 1920. Serial No. 395,346.

To all whom it may concern:

Be it known that we, JOHN SCHERNER, and EDWARD HUTCHENS, citizens of the United States, and residents of Cudahy, in the county of Milwaukee and State of Wisconsin, and the city of Eau Claire, in the county of Eau Claire and State of Wisconsin, respectively, have invented certain new and useful Improvements in Wrapping Machines; and we do hereby declare that the following is a full, clear, and exact description of the same, reference being had to the accompanying drawings, and to the numerals of reference marked thereon, which form a part of this specification.

This invention relates particularly to wrappings for automobile tires and the like and to machines for applying the wrapping, and is a division of our application Serial No. 88,563, which was filed in the United States Patent Office on April 3rd, 1916.

Automobile tires, coils of wire, strips of moulding, finished metal rods, and the like are often wrapped in paper or other fabric for the purpose of transportation. The wrapping fabric is usually cut in the form of strips which are spirally wound about the article to completely cover it. It is difficult to wrap the strip spirally and cause it to conform to the shape of the article. Moreover, when one of the convolutions of a spirally wound wrapping strip is broken or damaged, as frequently happens, the wrapping tends to unwind from the article, leaving it uncovered. It is accordingly important that a fabric strip be devised which will readily conform to the shape of the article about which it is to be wrapped, and that means be provided for rapidly applying the fabric in a neat and efficient manner so that when one of the convolutions of the wrapping is broken the remainder of the wrapping will not be affected.

An object of the present invention, therefore, is to provide an improved fabric strip for wrapping.

It is also an object of the invention to provide an improved fabric wrapping in such

form that it will conform to the shape of the article about which it is to be wound. 50

Other and further important objects of the invention will be apparent from the disclosures in the specification and the accompanying drawings.

The invention (in a preferred form) is 55 shown on the drawings and hereinafter more fully described.

On the drawings:

Figure 1 is a side elevation of a wrapping machine embodying the invention. 60

Figure 2 is an end elevation of the machine.

Figure 3 is a transverse section on the line 3—3 of Figure 1.

Figure 4 is a horizontal section on the line 65 4—4 of Figure 2.

Figure 5 is a sectional view of a portion of the shuttle of the machine showing the mounting of the fabric strip and the means for manipulating the edges of the strip for 70 causing the same to conform to the shape of the article.

Figure 6 is a sectional view of a wrapped tire.

Figure 7 is an elevation of the tire wrapping showing the manner in which the edges thereof are crimped or creased. 75

Figure 8 is a fragmentary detail of the wrapping strip showing the edge crimped.

Figure 9 is a transverse section of the 80 crimped strip.

As shown on the drawings: a

The machine is provided with a frame 1, upon which is mounted a driving motor 2. The driving shaft 3 has an annular gear 4 85 thereon, which drives a transverse shaft 5 through a suitable train of gears 6 and 7, which reduce the revolutions of the shaft 5 to the desired number. The upper gear wheel 4 is keyed or otherwise secured to the motor shaft, and the gear wheel 6 is mounted on a stub shaft 8, while the gear wheel 7 is loose on the transverse shaft 5 and is adapted to be locked to the same by the clutch 9 of any desired construction, having 90 a member slidably interlocked with the shaft

and movable into and out of engagement with the gear wheel 7. When the clutch is moved into engagement with the gear wheel 7, the shaft 5 is connected with and is adapted to be driven by the motor 2. The transverse shaft which is located at the rear portion of the machine is journalled in suitable bearings of the supporting frame and it has fixed to it a roll 11, having a suitable 10 friction facing and which is provided at opposite sides with flanges 12 and adapted to engage and rotate an annular shuttle 13. The transverse shaft 5 also carries a worm 14, which meshes with the worm wheel 15 15 keyed or otherwise secured to one of a pair of longitudinal shafts 16 and 17, which are simultaneously rotated in the same direction and which are connected by sprocket gearing located at the rear end of the longitudinal shafts 16 and 17, and consisting of a 20 sprocket chain 18 and sprocket wheels 19 fixed to the rear end of the shafts 16 and 17 and receiving and meshing with the said sprocket chain 18.

25 The shuttle 13, which is constructed of aluminum or other suitable material, is supported in position for rotary movement by the friction roller 11 and upper and lower front flange rollers 20 and 21, which are 30 mounted on suitable sub-shafts located at one side of the machine, the other side being open. The annular shuttle is provided with a hinged section 22 pivoted at 23 and constituting a door for enabling the annular 35 shuttle to be readily placed around a tire 23^a or other annular article, or to permit the tire 23^a or other article to be readily placed in and removed from the machine through said hinged section or door. The hinged 40 section or door is locked in its closed position by a spring actuated pin or bolt 24 slidably mounted on a hinge section 22 at the free end thereof, and movable into and out of engagement with the adjacent end of 45 the body portion of the shuttle and maintained normally in such engagement by coil spring 25. The latch is also equipped with an operating lever 26 pivoted at an intermediate point and having one of its arms 50 constituting a handle and its other arm connected with and adapted to move the pin or bolt 24 rearwardly against the action of the spring 25 to open the hinged door or section 22. The hinged door or section, 55 when opened, enables the shuttle to be readily disengaged by the upper and lower flanged rollers and the friction roller 11 to permit the removal of the shuttle for filling the same with adhesive material.

60 The interior of the shuttle 13 is hollow except for the gate 22 and forms a receptacle for liquid adhesive material, such as liquid glue or the like. A suitable filling opening 27 is provided which is normally closed by a plug or stop. As the shuttle 65 rotates the adhesive material is thrown outwardly by centrifugal force and caused to pass through an opening and be applied to a fabric strip in a manner hereinafter described. The shuttle 13, as shown in Figure 70 1, rotates in a clockwise direction and the opening through which the adhesive material passes to be applied to the strip is located at the rear end of the hollow interior of the receptacle so that the rotation 75 of the shuttle tends to cause the adhesive material to collect at the end of the shuttle in which the opening is located.

75 The tire or other article is supported and fed to the wrapping mechanism hereinafter described by the front portions of the longitudinal shafts 16 and 17, which are journalled in suitable bearings of the supporting frame of the machine. The front portions 80 28 and 29 are reduced and the tire or other article is supported and fed by the reduced portions. The reduced portion 28 is located in advance of the strip or ribbon 30 of wrapping material and in wrapping a 85 tire the tire is engaged at the bead by opposite squeezing rolls 31 and 32 set at an angle or inclination and adapted to engage and interlock with the tire at the base portion thereof for maintaining the tire in a 90 compact condition while the tire is being 95 wrapped. The rear squeezing roller 31 is permanently mounted on one of the bearings of the longitudinal shaft 16, and the other roller 32 is mounted on a pivot 33, which is carried by slidable sleeves 34 preferably mounted on the shaft 16 at the reduced portion thereof and maintained in engagement with the tire by a coiled spring 35 interposed between and whose ends are 100 engaged in the sleeve and the front bearing 36 of the reduced portion 28, and the sleeve 34 for urging the front or outer squeezing roller 32 inwardly or rearwardly. By this means the squeezing roller 32 is 105 maintained in engagement with the tire and is also held against rotary movement on the reduced portion 28 of the shaft 16.

110 The fabric strip, which may be paper, cloth, or any suitable material, is carried by a spool 39 that is arranged on a rotary spool holder 37 mounted on a horizontal stud or spindle 38. The inner end 40 of the spindle is threaded and tapped into the rotary shuttle. The spool is retained on the spool holder by a removable collar 41, and a locking washer 42, but any suitable device may, 115 of course, be employed as will be readily understood.

120 The ribbon of wrapping material is led from the spool over a horizontal feed tube 43 constituting a guide for the wrapping material and provided at its outer end with a head or flange 44, having its inner end 45

threaded and tapped into the rotary shuttle. The inner portion of the tubular guide 43 is provided with an outlet perforation 46, and the paper or cloth ribbon or strip is held against the perforation or discharge orifice by a spring 47, which is also adapted to constitute a closure or valve for the discharge orifice in event of breakage of the wrapping ribbon so that the glue or other adhesive material will not leak or waste.

The diameter of the feed tube 43 is reduced gradually for a part of its length near the outer end, being smallest at the base of the collar 44. A roller 70 conforming to the shape of the reduced portion is rotatably mounted on the shaft 71 and is held yieldably against said reduced portion and with its axis in the same vertical plane by the spring 72.

As the tape 30 is fed to the article or tire to be wrapped, the roller 70 co-acting with said portion provides a continuous series of crimps or accordion pleats 81, which, as the strip is applied to the article, are adapted to automatically fold or adjust themselves to cause a flat winding of the strip on the article and prevents buckling or other deformations thereof as the wrapping is applied to the article, and subsequent to its application.

When the clutch is thrown into operation, the shuttle is caused to revolve and the tire or other article is fed to the same at right angles thereto and the paper thus traveling around the tire or other article wraps the same spirally as it unwinds from the roll. As the edge of the paper or other material travels over the discharge aperture, centrifugal force acting on the glue or other adhesive material in the shuttle throws the glue against the edge of the paper and the ribbon of wrapping material is cemented or glued where it overlaps the paper beneath it. The bands of the wrapper are thus cemented or glued together, making it practically a one-piece wrapper, and due to the improved pleating of the wrapper as it is being applied this one-piece wrapper engages the article to be wrapped smoothly and evenly.

In order to enable the glue or other adhesive material to flow freely through the discharge aperture under the influence of centrifugal force, the shuttle is provided with a vent aperture 48, which is closed by needle valve 49 when the shuttle is stationary. The needle valve, which is in the form of a substantially L-shaped lever, is pivoted intermediate of its ends at 50 in a suitable bracket or support and its front portion is provided with the valve proper, while its rear portion is equipped with a weight 52 adapted when the shuttle is revolved to move outwardly through cen-

trifugal force and open the valve and permit air to enter the shuttle through the vent opening. As soon as the shuttle stops the valve is automatically closed by a spring 53, which is secured at one end to the weight and has its other end bearing against the shuttle as clearly shown in Figure 1 of the drawings. The weight is adjustable on the lever to secure the desired action of the spring and the weight. A cord or wire 54 is spread under the wrapper from an overhead spool 55 journaled in suitable bearings on the standard 56 of the supporting frame, but any suitable supporting means may of course be employed for mounting the spool of twine, wire or cord. The cord, wire or twine is bent downwardly from the spool and passes over a guide pulley 57 and is fed to the tire or other article preferably centrally of the tread as illustrated in Figure 1. The cord is interposed between the tire or other article and the wrapper and is adapted to be pulled to cut the wrapper and remove the same from the tire or other article. When the clutch is thrown out of operation by the means hereinafter described, the shuttle is engaged by the brake lever 58, fulcrumed at one end at 59 and provided with an engaging portion or shoe 60 and having a rearwardly extending arm, which is connected by rod or link 61, with an arm 62 of a rod shaft 63, having a pedal 64 mounted on it and also provided with an arm 65, which is connected by link or rod 67 with a clutch shifting lever 68. Said lever 68 is fulcrumed intermediate its ends at 69 and its upper end is connected with the clutch. When the clutch is thrown into engagement and the brake lever is moved out of engagement with the shuttle, and when the clutch is moved out of its engaging position, the brake is applied to the shuttle to stop the latter.

While we have herein shown and described a tire wrapping machine equipped with means whereby the crimped or pleated wrapping of this invention may be applied, it is to be understood that the crimping or pleating device may be conveniently used on any tire wrapping machine and that the crimped wrapping provided thereby is adapted to be used for wrapping any annular articles.

We are aware that numerous details may be varied through a wide range without departing from the principles of this invention, and we therefore do not purpose limiting the patent granted otherwise than necessitated by the prior art.

We claim as our invention:

1. A method of wrapping an annular article such as an automobile tire or the like which consists in winding a strip of

4

fabric about the article, crimping the edge of said strip as it is being wound to cause it to conform to the shape of the article and applying an adhesive to said strip to unite the convolutions of the winding.

2. A method of wrapping an annular article such as an automobile tire or the like, which consists in winding a strip of material about the article and crimping the edge of said strip as it is being wound to cause it to conform to the shape of the article.

In testimony whereof, we have hereunto subscribed our names in the presence of two subscribing witnesses.
